United States Patent Office

Des. 200,535
Patented Mar. 9, 1965

200,535

CHAIR

Robert E. Kjer Jakobsen, Manhattan Beach, Calif., assignor to Schlumberger Limited (Schlumberger N.V.), Houston, Tex., a corporation of the Netherlands Antilles

Filed Mar. 31, 1964, Ser. No. 79,270

Term of patent 14 years

(Cl. D15—1)

FIG. 1 is a front perspective view of a chair showing my design; and

FIG. 2 is a rear perspective view thereof.

I claim:

The ornamental design for a chair, substantially as shown.
